United States Patent Office.

CHRISTOPHER F. CONRAD, OF ADRIAN, MICHIGAN.

Letters Patent No. 72,721, dated December 31, 1867.

IMPROVEMENT IN WIND-WORMS FOR BLACKSMITHS' BELLOWS.

The Schedule referred to in these Letters Patent and making part of the same.

TO ALL WHOM IT MAY CONCERN:

Be it known that I, CHRISTOPHER F. CONRAD, of the city of Adrian, in the county of Lenawee, and State of Michigan, have invented a new and useful Improvement in Wind-Worms for Blacksmiths' Bellows; and I do hereby declare that the following is a clear and exact description, which will enable others skilled in the art to make and use the same, reference being had to the accompanying drawings, and to the letters of reference marked thereon.

My invention consists in providing the nozzle of blacksmiths' bellows with a serpentine channel, placed between the fire of the forge and the nozzle of the bellows, and through which the wind is forced while passing from the latter to the former, thereby softening the blast and causing a more even, steady, and prolonged current of wind to be forced into the fire, and at the same time preventing the gas from entering into the bellows, and also creating a better heat; all to be made of iron. In the drawings—

Figure 1 is a perspective view of the interior serpentine channel or air-passage, with its surrounding walls and floor.

Figure 2 is a perspective view of the lid designed to cover over and be screwed fast upon the upper surface of that portion represented by fig. 1, thus completing the interior surface of the channel.

C B, in fig. 1, represent the termini of the serpentine channel, the nozzle of the bellows fitting air-tight around the thimble A, fig. 2, and another short iron thimble fitting in like manner to the thimble D, and communicating with the fire in the forge. The current of wind, when forced into the fire, will then take the direction indicated by the arrows. The walls of the worm are to consist of two iron castings, in the form represented by figs. 1 and 2, both to be fastened together with bolts and screws $\alpha \alpha \alpha$, &c., and suitably packed so as to render them air-tight. The worm is to have six or any other suitable number of serpentine changes.

Claim.

What I claim as my invention, and desire to secure by Letters Patent, is—

The serpentine wind-channel C B, constructed and operating in the manner and for the purposes substantially as set forth.
